KNITTING NEEDLE

Roy C. Amidon, Reading, Pa., assignor to Vanity
Fair Mills, Inc., a corporation of Pennsylvania

Application January 28, 1944, Serial No. 519,814

2 Claims. (Cl. 66—120)

My invention relates to the art of knitting and it more specifically has reference to the needles and knock-over sinkers used on warp knitting machines.

Primarily the invention has for an object to provide a needle and sinker combination which is particularly adapted for use in knitting machines of the kind disclosed in my application Serial Number 506,561, filed October 16, 1943.

Other objects of the invention are: to provide a knitting needle of such reinforced construction that the needles may be made of exceptionally fine gauge without bending or breaking under the usual strains and stresses encountered in high-speed warp knitting machines; to provide a needle in which the advantages of a slide-hook closer are combined with that of a springy beard; to provide a needle of such construction that when the weakest part of the needle passes through the loop in knocking-over, the loop will be looser than when it is drawn about that part of the shank of the needle around which the loop is cast while the opening of the needle is receiving thread or yarn by the action of the thread guides, thereby relieving the needle from strain at its weakest place; to provide a needle in which the springy-beard portion need flex only slightly while the thread or yarn is passing out of the hook; to provide a needle of such construction that when pulling a loop through a previously formed loop the pull is substantially directed along the length of the needle and the bend of the hook of the needle is reinforced by the hook-opening closer.

Again, it is an object to provide a sinker with means for supporting the needle sidewise and to provide the sinker with a higher knock-over portion than the nib in order to make it unnecessary to bring the needle down into the sinker as deep as heretofore and thus enable a shorter stroke of the needle to be used in the knitting process.

Other objects will in part be obvious and in part will be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawing, in which:

Fig. 1 is an elevation, on a magnified scale, illustrating the workings of the invention.

Fig. 2 is a vertical longitudinal section of a por-

tion of a needle in the closed-hook position, taken on the line 2—2 of Fig. 3.

Fig. 3 is a cross section on the line 3—3 of Fig. 2.

Fig. 4 is a cross section on the line 4—4 of Fig. 2.

Fig. 5 is a vertical section on the line 5—5 of Fig. 1 with the needle in dotted line position.

In the drawing, in which like numerals of reference indicate like parts in all the figures, it will be seen that the needle as a whole is composed of two sections. One of these sections comprises a shank 1 having a base 2 and an extension 4 of a reduced thickness, a bend 5, and a beard 6 that lies—in general—parallel with the portion 4, the beard 6 including the portion 6a which closes the throat or opening of the hook. The other of the two sections includes the shank 7, having a base 8, an extension 10 of a reduced thickness, a bend 11, and a portion 12 that lies—in general—parallel to the portion 10 and whose end is spaced from the shaft to provide the throat opening of the hook, that is closable by the beard portion 6a.

The shank 1 has a tongue and groove engagement 3 with the shank 7 and the portion 12 is widened and grooved, as at 13, to receive the beard 6, while a recess 14 is provided in the shank 7 to receive the end of the beard.

It will be seen that the portion 12 of the inner needle extends a substantial distance parallel to the portion 10 and is comparatively rigid so that when the throat of the needle 7 is closed by the portion 6a of the beard 6 the portion 12 serves as a substantial support or brace for the beard 6, 6a while the thread is being cast about the needle. Further when the throat of the needle is closed the portions 6, 12, and 8, 11, and 10, 4 are in full contact throughout, thus making the hook end of the needle as a whole comparatively rigid and enabling the needle to be constructed as a very fine gauge needle. The combined or overall perimeters of the shanks of the two sections being greater than the overall perimeter of the hook portions of the needle, provides means for pulling out the loops so that as the needle knocks over the loops will slip over the hooks easily.

In order to provide support for the hook end of the needle while the thread guide or guides are laying the thread about the needle, I provide the sinker 15 with a thickened portion 16 on each blade, thereby bringing the support for the needle as near the hook end of the needle as possible at that time.

In Fig. 1 the full lines indicate the needle in the raised position with the thread guides 20 and 21 casting the thread about the needle to enter

the throat thereof. In this position of the needle the throat of the needle is open; the light dotted lines indicate the needle on its upward journey, slipping the loop L' out of the hook of the needle; the heavier dotted lines show the position of the needle at the lower limit of its stroke in pulling loops L^2 through the previously formed loop L' at the raised knock-over portion 18 of the sinker.

Any suitable means (not shown) may be provided for positively reciprocating the needle and its separate parts in harmony with the knitting process, but as such means, *per se*, is not a part of the present invention, illustration thereof is thought to be unnecessary.

From the foregoing description, taken in connection with the accompanying drawing, it is thought that the construction, operation and advantages of the invention will be clear to those skilled in the art to which it appertains.

What I claim is:

1. A knitting needle comprising two bodies of approximately the same thickness, one embraced by the other, each of said bodies including a shank and a hook, the hook of the inner body having a throat, the hook of the outer body having a springy beard including a portion serving

as a throat closer when the two bodies are closed together, the front part of the hook of the inner section being straight and the beard being straight and held in sliding contact with said front part throughout its length during substantially the full time the two bodies are moving the one along the other, the combined perimeters of the shanks of the two sections being greater than the over-all perimeter of the hook portions of the needle.

2. A knitting needle composed of two complementary sections of equal thickness, each section comprising a base, a shank and a hook, said sections having tongue and groove engagement along the shanks and along the front portions only of the hooks, the outer one of the hooks having a springy beard portion which extends below the end of the inner one of the hooks when the bends of the hooks are together, the shank of the section which has the inner hook having a recess releasably to receive the point of the beard when the bends of the hooks are together, the combined perimeters of the shanks of the two sections being greater than the over-all perimeter of the hook portions of the needle.

ROY C. AMIDON.
